RESILIENT RELOADING CLIP FOR REVOLVERS

John M. Hunt, San Mateo, Calif.

Application April 16, 1956, Serial No. 578,462

10 Claims. (Cl. 42—89)

This invention relates to reloading clips for revolvers, whereby a full complement of replacement cartridges can be inserted simultaneously into the revolver cylinder by a quick, substantially continuous hand motion.

Because of its great reliability and other advantages, the revolver is a favorite weapon of sportsmen, police officers and felons. Its greatest disadvantage is the relatively long time, as compared to automatic pistols and the like, required for reloading the revolver cylinder with replacement cartridges. In some situations, such as a gun fight or the hot pursuit of the criminal by a police officer, this disadvantage can inconvenience and endanger the user of the revolver. A practical reloading clip, holding a full complement of replacement cartridges ready for instant simultaneous insertion into the revolver cylinder, would be highly advantageous to police officers and other users of revolvers.

Although reloading clips for revolvers have heretofore been proposed, the prior reloading clips have had some or all of several practical disadvantages that have prevented their extensive use and general adoption. Among such practical disadvantages are mechanical complexity, lack of reliability in holding the replacement cartridges in position and in condition for instant reloading, inconvenience and difficulty in the manner of use, particularly with respect to removing the clip from the cartridges after they have been inserted into the revolver cylinder, and other disadvantages that are apparent upon consideration of the various reloading clips heretofore proposed. Therefore, despite the substantial need for a practical reloading clip, and despite numerous prior attempts to supply this need, dependable, quick reloading of revolvers has heretofore been accomplished only in fiction and "Western" movies.

Accordingly, an object of this invention is to provide a simple, convenient and reliable, practical reloading clip for revolvers. Another object is to provide a reloading clip whereby a full complement of replacement cartridges can be inserted simultaneously into the cylinder of a revolver with a quick, substantially continuous movement of the hand. Another object is to provide an improved reloading clip whereby a revolver can be reloaded in less than one-quarter the time heretofore required. Another object is to provide an improved reloading clip whereby a revolver can be reloaded quickly while the user is wearing gloves. Another object is to provide an improved reloading clip for revolvers that reliably holds the replacement cartridges in position for instant simultaneous insertion into a revolver cylinder, while the loaded clip is carried in a coat pocket or any other convenient place, despite shaking, dropping or striking against other objects. Another object is to provide a reloading clip for revolvers having small cylinders such that the rims of cartridges in the cylinder may touch or nearly touch one another. Another object is to provide a safe, quickly accessible revolver loading means for home owners and others who, for reasons of safety, normally keep their revolvers unloaded.

2

Another object of this invention is to provide an improved revolver reloading clip and cannister, suitable for attachment to a cartridge belt or other article of clothing, wherein the loaded clip is instantly available and is removable from the cannister by a quick, substantially continuous movement of the hand. Another object is to provide an improved revolver reloading clip and cannister wherein the loaded clip remains securely in place in the cannister despite shaking or brushing against other objects as may occur in rough-and-tumble combat. Still another object is to provide an improved revolver reloading clip and cannister that is moistureproof, weatherproof and rattleproof.

Briefly stated, in accordance with certain aspects of this invention whereby the foregoing and other objects and advantages are achieved, an improved reloading clip for revolvers is a one-piece flat-bottomed cup of resilient material, preferably rubber. The outside bottom surface of the cup contains a plurality of flat-topped circular recesses, each adapted to receive and seat the flanged butt end of a cartridge. These recesses are arranged in a circle, and they correspond in number and position to the cartridge chambers in the cylinder of a revolver. A resilient flange extends substantially entirely around the lip of each cartridge-receiving recess and is adapted to grip securely the flanged butt end of the cartridge seated in the recess so that, when the clip is loaded, the plurality of recesses securely hold a full complement of replacement cartridges ready for instant simultaneous insertion into the cylinder of a revolver. Thus the cartridges are securely and reliably held in position, despite jarring or striking against other objects such as may occur when the loaded clip is carried in a coat pocket or any other convenient place.

When the revolver is to be reloaded, the lip of the cup is grasped in one hand (between the thumb and forefinger, for example) and the cartridges are inserted simultaneously into the revolver cylinder. Without changing the manner of gripping the cup, the reloading clip can be "peeled" away from the butt end of the cartridges by a quick sidewise motion of the hand, so that the entire reloading process can be accomplished by a quick, substantially continuous movement of one hand, even when the user is wearing gloves. A thickened ring around the lip of the cup facilitates secure gripping of the clip, particularly with a gloved hand.

Preferably, the outside bottom surface of the cup contains an annular groove extending substantially through the centers of the circular recesses and having a depth at least as great as that of the aforesaid resilient flanges. This provides in each flange two breaks or gaps located substantially at the points nearest the adjacent recesses, so that the resilient material of the cup will not be caught or pinched between adjacent cartridge flanges when the clip is "peeled" away from the cartridges. This feature permits use of the improved reloading clip with revolvers having small cylinders such that the rims of cartridges in the cylinder may touch or nearly touch one another.

The loaded clips may be carried loose in a coat pocket or any other convenient place. Because of the flanges that extend entirely around the flanged butt end of each cartridge, except for the two small breaks provided by the aforesaid annular groove, the cartridges are securely held in position for instant reloading despite reasonable shaking, dropping or striking against other objects. However, at times it is desirable to provide a weatherproof, rattleproof cannister for protecting the cartridges and keeping them in perfect condition for instant use. There are occasions when the rattleproof feature is of great importance to law enforcement officers and others.

A preferred type of cannister is a metal cup having an inwardly crimped lip. A clasp may be provided for

attaching the cannister to a cartridge belt, or to an ordinary belt or to any other suitable article of clothing. The bottom of the metal cup contains a resilient wafer, preferably of sponge rubber. The bottom of the rubber reloading clip fits into the open top of the metal cup and is securely held in position by the inwardly crimped lip. The cartridges seated in the loaded clip extend downward inside the cannister and their noses rest against and press into the sponge rubber wafer. Thus each cartridge is held securely in position and the assembly is rattleproof. The inwardly crimped lip of the metal cup grips the bottom of the rubber reloading clip to form a moistureproof, dustproof seal that protects the cartridges from the weather and keeps them in perfect condition for instant use over long periods of time.

The reloading clip extends upward from the top of the cannister so that the loading clip can easily and quickly be grasped by the hand. A quick upward jerk removes the loaded clip from the cannister and, without changing the grip of the hand on the reloading clip, the cartridges can be inserted into the revolver cylinder and the clip can be "peeled" off with a quick, substantially continuous one-hand motion. Nevertheless, the crimped lip of the cannister grips the bottom of the reloading clip securely enough and the reloading clip itself is sufficiently flexible and resilient that reasonable shaking or the brushing of other objects against the clip, as may occur during rough-and-tumble combat, will not dislodge the reloading clip from the cannister.

The invention will be better understood from the following detailed description of an illustrative embodiment taken in connection with the accompanying drawing, and its scope will be pointed out in the appended claims. In the drawing,

Fig. 1 is a perspective view of a loaded reloading clip for revolvers embodying principles of this invention;

Fig. 2 is a bottom view of the same reloading clip, drawn to a larger scale and without the cartridges;

Fig. 3 is a section along the lines 3—3 of Fig. 2;

Fig. 4 is a section of a loaded loading clip and cannister embodying principles of this invention; and

Fig. 5 is a schematic view, partly in section, showing how the reloading clip may be "peeled" off the cartridges after they are inserted into the cylinder of a revolver.

Referring to Figs. 1 through 3 of the drawing, the improved reloading clip for revolvers is a one-piece resilient rubber cup 1 having a substantially flat outside bottom surface 2. This flat bottom surface contains a plurality of flat-topped circular recesses 3, 4, 5, 6, 7 and 8. Recesses 3 through 8 are arranged in a circle concentric with the bottom of cup 1, as shown, and correspond in number and position to the cartridge chambers of a revolver cylinder. The flat top of each recess provides a seat for receiving the flanged butt end of a cartridge. The clip is loaded by inserting into respective ones of the recesses the butt ends of a plurality of cartridges 9, 10, 11, 12, 13 and 14, as shown in Fig. 1.

Each of the cartridge-receiving recesses (recess 8, for example) has a resilient flange 15 extending substantially entirely around its lip, as shown. Resilient flanges 15 are parts of cup 1, and are of the same resilient material, preferably rubber. These flanges underlie and grip the flanged butt ends of cartridges seated in the recesses and securely hold the cartridges in position for instant simultaneous insertion into a revolver cylinder. Because flanges 15 surround substantially the entire base of each cartridge, the cartridges are reliably and securely held in position despite reasonable shaking or dropping of the loaded clip or striking against other objects, such as will occur, for example, when the loaded clips are carried in a coat pocket or the like. However, the resilience of cup 1 and flanges 15 permits easy loading of the clip and also permits the clip to be "peeled" quickly from the cartridges after they have been inserted into the revolver cylinder, as it hereinafter more fully explained.

A plurality of grooves, 16, 17, 18, 19, 20 and 21 are provided between respective ones of recesses 3 through 8, as shown. Grooves 16 through 21 preferably are short arcuate portions of a single circular groove in the flat outside bottom surface 2 of cup 1. The circular groove is broken into sections by recesses 3 through 8, with which it merges. This circular groove passes through the centers of the cartridge-receiving recesses, and provides in each of the flanges 15 two breaks or gaps substantially at the points nearest the two adjacent recesses.

The depth of the circular groove is equal to or slightly greater than the depth of flanges 15. The circular groove is especially important in reloading clips for use with revolvers having small cylinders such that the butt-end flanges of cartridges in the revolver cylinder touch or nearly touch one another. The two breaks in each flange keep the resilient flange material from being caught or pinched between adjacent cartridges when the reloading clip is "peeled" off as hereinafter explained. The two breaks in each flange also facilitate loading of the clip.

The open top of cup 1 preferably is of somewhat smaller diameter than the bottom of the cup so that the sides of the cup slope inward as shown. The lip of the cup preferably is thickened to form a ring 22 around the top of the cup. The inside bottom surface of cup 1 preferably has an annular raised portion 23 and the outside bottom surface of the cup preferably has a dome-shaped central recess 24, as shown, so that the bottom of cup 1 is relatively thin at its center and at its periphery and is relatively thick between the center and the periphery. This shape makes it easier to "peel" the reloading clip from the cartridges after they are inserted into the revolver cylinder and provides substantial parallel alinement while cartridges are seated in clip for easy and direct insertion of the cartridges into the cylinder of a revolver. Recess 24 also provides clearance for the pin that is located in the center of many revolver cylinders.

Referring now to Fig. 4 of the drawing, a weatherproof and rattleproof cannister for protecting the cartridges loaded in a clip comprises an open-topped metal can 25. A clasp 26 may be provided for attaching the cannister to a belt or other article of clothing. A resilient wafer 27, preferably of sponge rubber, covers the inside bottom surface of can 25. The lip 28 of can 25 is crimped inward, as shown. The bottom of resilient reloading clip 1 fits into the open top of can 25 and is securely gripped and held in place by the inwardly crimped lip 28, forming a moistureproof and dustproof seal to protect the cartridges from the weather and from dirt. The cartridges seated in the recesses of clip 1 extend downward inside of can 25 and their noses rest on and press into sponge rubber wafer 27. As a result the cartridges are securely held in place and the assembly is rattleproof. This cannister keeps the cartridges in perfect condition for instant use over long periods of time.

Because reloading clip 1 is securely gripped by the crimped lip 28 of the cannister and also because clip 1 is of resilient material, the loaded clip is securely held in the cannister and is not displaced by reasonable shaking or by other objects brushing against the clip, as may occur during rough-and-tumble combat. However, the loaded clip can quickly and easily be withdrawn from the cannister simply by grasping the lip or the sides of clip 1, between the thumb and forefinger for example, and quickly pulling upward on the clip. Ring 22 makes it easier to get a secure grip on clip 1 which may be done, for example, by inserting either the thumb or the forefinger into cup 1 and pressing against the outside of cup 1 with the other. Even when the user is wearing gloves the loaded clip is instantly available.

Without changing the grip of the hand on clip 1 the full complement of replacement cartridges can be inserted simultaneously into the cylinder of a revolver. A quick

sidewise motion of the hand will then "peel" the reloading clip 1 away from the cartridges that have been inserted into the revolver cylinder, as is shown in Fig. 5.

Referring now to Fig. 5, a full complement of replacement cartridges has just been inserted into the cylinder 29 of a revolver. The hand grasping clip 1 is quickly moved to the right and as this is done clip 1 quickly and easily "peels" away from the flanged butt ends of the cartridges.

From the foregoing description it is apparent that the improved cartridge clip makes possible reliable reloading of a revolver in a fraction of the time required heretofore. The clip may be grasped with the thumb and forefinger of one hand, pulled out of the cannister, inserted into the revolver cylinder and "peeled" off, all without changing the grip of the hand on the reloading clip, in a quick, substantially continuous one-hand motion. It is not required that the reloading clip be grasped in any particular manner. For example, the thumb or any finger can be inserted into the open top of the reloading clip, or the user can simply grab the clip without inserting any finger into the opening. This feature greatly facilitates reloading in the shortest possible time.

Furthermore, since the cartridges are held securely in place by the resilient flanges that surround substantially the entire base of each cartridge, the full complement of cartridges is always in proper position for immediate simultaneous insertion into the revolver magazine and there is little or no chance that a displaced cartridge will foul up the reloading operation. The loaded clips may be carried in a coat pocket if desired, or use may be made of the cannister that keeps the cartridges in perfect condition for instant use, and has the important advantage of being rattleproof. The improved reloading clip is exceptionally small and compact, providing maximum clearance so that it is readily usable with revolvers having protruding members that would preclude the use of more bulky reloading clips.

It should be understood that this invention in its broader aspects is not limited to the specific embodiment herein illustrated and described and that the following claims are intended to cover all changes and modifications that do not depart from the true spirit and scope of the invention.

What is claimed is:

1. A reloading clip for revolvers, comprising a resilient cup having annular sides, a closed bottom and an open top, said cup having a substantially flat bottom outside surface, said surface containing a plurality of recesses each adapted to receive the butt end of a revolver cartridge, said recesses being arranged in a circle holding a plurality of cartridges in position for simultaneous insertion into the cylinder of a revolver.

2. A reloading clip for revolvers, comprising a one-piece resilient cup having annular sides, a closed bottom and an open top, said cup having a substantially flat bottom outside surface, said surface containing a plurality of round flat-topped recesses each adapted to receive and seat the flanged butt end of a revolver cartridge, there being a resilient flange extending substantially entirely around the lip of each of said recesses and adapted to grip the flanged end of the cartridge seated in the recess and to support said flanged end against lateral motion in any direction, said recesses being arranged in a circle for holding a plurality of cartridges in position for simultaneous insertion into the magazine of a revolver.

3. A reloading clip for revolvers, comprising a one-piece unit of resilient material having a substantially flat bottom surface, said surface containing a plurality of round recesses each adapted to receive the flanged butt end of a revolver cartridge, there being a resilient flange extending substantially entirely around the lip of each of said recesses and adapted to grip the flanged end of a

cartridge seated in the recess, there being only two breaks in each of said flanges, said breaks being respectively located substantially at the points nearest the two adjacent recesses so that the flange material will not be pinched between adjacent cartridges, said recesses being arranged in a circle for holding a plurality of cartridges in position for simultaneous insertion into a revolver cylinder.

4. A reloading clip for revolvers, comprising a resilient cup having annular sides, a closed bottom and an open top, said cup having a substantially flat bottom outside surface, said surface containing a plurality of round recesses each adapted to receive the flanged butt end of a revolver cartridge, there being a resilient flange extending substantially entirely around the lip of each of said recesses and adapted to grip the flanged end of a cartridge seated in the recess, said recesses being arranged in a circle for holding a plurality of cartridges in position for simultaneous insertion into the magazine of a revolver, said surface containing a circular groove passing substantially through the centers of said circular recesses, said groove having a depth at least as great as the depth of said flanges to provide in each flange only two breaks substantially at the points nearest the two adjacent recesses.

5. A reloading clip for revolvers, comprising a flat-bottomed cup of resilient material, said cup having annular sides with a thickened lip forming a ring around its top, the outside bottom surface of said cup containing a plurality of recesses each adapted to receive the butt end of a cartridge, said recesses corresponding in number and position to the cartridge chambers of a revolver cylinder.

6. A reloading clip for revolvers, comprising a flat-bottomed cup of resilient material, said cup having annular sides, a closed bottom, and an open top of smaller diameter than its bottom so that its sides slope inward, the outside bottom surface of said cup containing a plurality of recesses each adapted to receive the butt end of a cartridge, said recesses corresponding in number and position to the cartridge chambers of a revolver cylinder.

7. A reloading clip for revolvers, comprising a flat-bottomed cup of resilient material, said cup having annular sides, a closed bottom and an open top, the outside bottom surface of said cup containing a plurality of recesses each adapted to receive the butt end of a cartridge, said recesses being arranged in a circle concentric with the bottom of said cup, the bottom of said cup being relatively thin at its center and at its periphery and having a thicker annular section between its center and its periphery.

8. A reloading clip for revolvers, comprising a one-piece flat-bottomed cup of resilient rubber, said cup having an open top of smaller diameter than its bottom so that its sides slope inward, said cup having a thickened lip forming a ring around its top, said cup having a substantially flat bottom outside surface containing a plurality of round flat-topped recesses each adapted to receive and seat the flanged butt end of a revolver cartridge, there being a resilient flange extending substantially entirely around the lip of each of said recesses and adapted to grip the flanged end of a cartridge seated in the recess, said flanges being parts of said one-piece cup and of the same material, said recesses being arranged in a circle concentric with the bottom of said cup for holding a plurality of cartridges in position for simultaneous insertion into a revolver cylinder, said outside bottom surface containing a circular groove passing substantially through the centers of said circular recesses, said groove having a depth at least as great as the depth of said flanges to provide in each flange two breaks substantially at the points nearest the two adjacent recesses, said flanges except for the aforesaid breaks extending entirely around the bases of cartridges seated in said recesses, the bottom of said cup being relatively thin at its center and at

its periphery and having a thicker annular section between its center and its periphery.

9. In combination, a reloading clip for revolvers and a cannister, said reloading clip being a resilient cup having a substantially flat bottom surface, said surface containing a plurality of recesses for seating the butt ends of revolver cartridges, said cannister being a can having an open top with an inwardly crimped lip, the bottom of said cup fitting into the open top of said can and being securely gripped by said inwardly crimped lip, the cartridges seated in said recesses extending downward inside of said can.

10. In combination, a reloading clip for revolvers and a cannister, said reloading clip being a rubber cup having a substantially flat bottom surface, said surface containing a plurality of recesses for seating the butt ends of revolver cartridges, said cannister being a metal can having an open top with an inwardly crimped lip, the

bottom of said rubber cup fitting into the open top of said can and being securely gripped by said inwardly crimped lip to form a moistureproof and dustproof seal, a resilient wafer of sponge rubber covering the inside bottom surface of said can, the cartridges seated in said recesses extending downward inside said can with their noses resting against and pressing into said wafer to form a rattleproof assembly.
